HEATING OF FLUIDS

Lev A. Mekler, Chicago, Ill., assignor to Universal
Oil Products Company, Chicago, Ill., a corpora-
tion of Delaware

Application December 14, 1932, Serial No. 647,167

1 Claim. (Cl. 196—110)

This application is a continuation in part of my co-pending application, Serial No. 414,270, filed December 16, 1929 now U. S. Patent No. 2,009,092.

5 This invention particularly refers to a furnace of improved design, specially adapted to heat hydrocarbon oils to the high temperatures required for their conversion and also embodies the methods of heat treatment made possible by the improved form of furnace.

10 Hydrocarbon oils of different characteristics require different methods of heating in order to subject them to the conversion conditions most suitable for the production of maximum yields 15 of the desired products. It is the purpose of the present invention to provide a furnace of improved form wherein better control is obtained over the conditions of heating to which an oil is subjected and wherein the conditions may be varied to suit requirements of the particular type 20 of oil undergoing treatment.

It is the purpose of the present invention to control not only the maximum rate of heating and the maximum temperature to which the oil 25 is heated in the furnace but also to positively and independently control the rate at which the oil is heated in various sections of the fluid conduit through which it passes in the furnace. In this manner the type of heating curve obtained 30 by plotting the temperature attained by the oil at various points throughout the heating coil is positively controlled so that any oil of known characteristics may be subjected to the type of heat treatment known to be best adapted to produce the desired results from that particular oil.

35 It is not within the sphere of the present invention to attempt to classify the oils of known cracking characteristics with respect to the type of heating curve most suitable for each oil, nor is it the intention of the present invention to generalize or specify the type of heating curve most suitable for different classes or groups of hydrocarbon oils. It is rather the purpose of the present invention to provide an improved 40 form of furnace wherein each of a wide variety of oils may be subjected to the previously determined conditions of heat treatment most suitable for the particular oil.

45 A specific embodiment of the apparatus of the present invention may comprise a furnace of symmetrical design with respect to the type of heating employed on opposite sides of a plane through the vertical center line of the furnace having a fluid conduit supplied substantially with 50 convection heat in the central portion of the fur-

nace and fluid conduits supplied substantially with radiant heat on opposite sides of the furnace located along the furnace roof and side walls, a combustion zone with means for independently supplying combustibles thereto being located on each side of the furnace whereby the heating conditions on opposite sides of the furnace are independently controlled, thereby independently controlling the rate of heating to which the oil is subjected in the fluid conduit on opposite sides 10 of the furnace.

The accompanying diagrammatic drawings, Figs. 1, 2 and 3 illustrates one specific form of furnace embodying the features of the present invention and the methods of operating the furnace to fulfill the objects of the present invention will be more apparent with reference to the drawings and the following description thereof.

Fig. 1 is a cross-sectional end-view of the furnace.

Fig. 2 is a sectional plan view of the same structure taken along a horizontal plane indicated by the line 2—2 in Fig. 1 and

Fig. 3 is a sectional elevation of the same furnace structure taken through a vertical plane 25 indicated by the line 3—3 in Fig. 1.

In the drawings the side walls are designated by the numbers 1 and 1', the end-walls are 2 and 2', the roof 3 and the floor 4. Bridge walls 5 and 5' separate combustion and radiant heating zone 6, located, as here illustrated, on the right hand side of the furnace from a similar combustion and radiant heating zone 6' located on the opposite side of the furnace.

Fluid heating zone 7 is located between bridge walls 5 and 5' and contains a bank 8 of tubes 9 heated substantially by convection heat from the furnace gases having passed from combustion zones 6 and 6' over bridge walls 5 and 5', respectively, into heating zone 7, the commingled gases 40 from both combustion zones passing downward around the tubes in bank 8 and out of the furnace through a flue 10, controlled by damper 11 to a stack (not shown).

A bank 12 of tubes 13 is located along the side 45 1 and right hand half of roof 3 and is supplied substantially with radiant heat from the materials undergoing combustion in combustion zone 6 and from the hot refractory walls of this zone of the furnace. Another bank 12' of tubes 50 13' is located along the side wall 1' and left hand half of roof 3 and the tubes of this bank are subjected substantially to radiant heat from the flame in combustion zone 6' and the hot refractory surfaces of this zone of the furnace.

Combustion zone 6 is supplied with combustibles through firing tunnels 14 located along the side wall 1 of the furnace, one or any number of a plurality of similar firing tunnels being provided. A plurality of firing tunnels, as shown in the drawings, is preferred in order to secure uniform distribution of combustibles along the entire length of the combustion zone, thereby securing the even distribution of heat along the length 10 of heating tubes 12. In the case here illustrated, each firing tunnel consists of a fuel duct 15 to which any desired form of fuel such as oil, gas or pulverized solid fuel is supplied through a burner 21 of any suitable form, together with air 15 or other combustion supporting material. Ducts 16 and 17 located, respectively, above and below fuel duct 15 are provided for the purpose of supplying auxiliary air or steam to the combustion zone. Ducts 16 and 17 contain regulating dampers 18 and 19, respectively.

One or a plurality of similar firing tunnels 14' located along side wall 1' of the furnace supplies combustibles to combustion zone 6'. Firing tunnels 14' are preferably similar to firing tunnels 14 and, in the case illustrated, the description of the various parts and the appurtenances to firing tunnels 14 also applies to tunnels 14', primed numbers being used to designate the parts of firing tunnels 14', corresponding to the parts 30 of firing tunnels 14.

By means of separate combustion zones 6 and 6', separately supplied with combustibles, as described, firing conditions on opposite sides of the furnace may be independently controlled, there- 35 by independently controlling the heating conditions around tube banks 12 and 12' whereby the rate of heating to which the oil is subjected during its passage through each tube bank is independently controlled.

40 The tubes 9, 13 and 13' of banks 8, 12 and 12', respectively, extend between the end walls 2 and 2' of the furnace and in the case here illustrated are connected in series by return bends 28 of any suitable form and in Fig. 1 is illustrated one spe- 45 cific flow through the entire heating coil con-

sisting of tube banks 8, 12 and 12'. In the case illustrated, the oil enters the lower row of tubes in bank 8, passing in series through adjacent tubes in each row of this bank and out of the top row of bank 8 into the lower side wall tube 5 of bank 12, passing through adjacent tubes of this bank in series and out of the last roof tube in bank 12 into the adjacent roof tube of bank 12' on the opposite side of the furnace, passing through the adjacent tubes of bank 12' in series 10 and finally being discharged out of the furnace from the lower side wall tube in bank 12'.

It will be understood, however, that any desired flow of oil through each tube bank may be employed within the scope of the invention and 15 that the various tube banks may be connected in any desired sequence and that the direction of flow through any tube bank may be the same or the reverse of that shown in Fig. 1. The particular flow through the heating coil may be chosen 20 to suit requirements, as may the furnace conditions employed in opposite sides of the furnace, and it is not intended to impose limitations of any specific flow or furnace conditions upon the broad spirit and scope of the invention. 25

I claim as my invention:

An oil heating apparatus comprising a furnace having side walls, end walls, a roof and a floor, a pair of spaced bridge walls dividing the furnace into two outer compartments and a central compartment, a plurality of horizontally spaced fuel ducts, each provided with a burner, extending through each of said side walls adjacent the floor and adapted to project at least partially burned fuel toward one of said bridge walls, air ducts contiguous to and positioned above and below each of the fuel ducts, means for passing combustion gases from both said outer compartments through the central compartment, heating tubes in each of the outer compartments disposed 30 out of the main path of combustion gases therethrough, and additional heating tubes in the central compartment disposed in the path of the combustion gases therethrough. 35
